(57) **CLAIM**

The ornamental design for a furniture piece, as shown and described.

DESCRIPTION

FIG. 1 is a right, top, front perspective view of a furniture piece according to our new design;

FIG. 2 is a front elevational view thereof;

FIG. 3 is a rear elevational view thereof;

FIG. 4 is a right side elevational view thereof, the left side elevational view thereof being a mirror image of the right side shown; and,

FIG. 5 is a top plan view thereof.

The nature of this product is piece of furniture, such as a bench, cabinet, table and the like.
